BY

John J. Kerkhoff
ATTY.

UNITED STATES PATENT OFFICE

THEODOR KERKHOFF, OF HAMBURG, GERMANY

FORM FOR NECKTIES

Application filed June 12, 1928, Serial No. 284,748, and in Germany August 25, 1927.

This invention relates to improvements in forms for neckties, and more particularly to a form about which a bow tie may be tied, and then positioned over a collar button without having the tie encircle the neck of the wearer.

Having the tie elements are held in the various forms
An object of the invention is to provide an improved form for neckties, which will support a pivoted tie bar adapted to be held in raised position when a bow tie is being tied thereon, and moved to its normal or lower position to approximately cover the button hole in the form when the tie is to be worn.

A further object of the invention is to provide a flexible and resilient form for neckties which will support a tie bar pivoted between its opposite ends, and tension the bar when it is in its upper position ready to receive a bow tie, and also clamp the tie bar in its lower or operative position when the form and tie are to be worn.

Other objects will appear as the description proceeds.

In the accompanying drawings which form a part of my application:

25. Figure 1 is a front elevation of my improved form for neckties showing the tie bar in lower or operative position.

Figure 2 is a front elevation of the form showing the tie bar in raised position to receive a bow tie.

Figure 3 is a plan view of the necktie form in position as shown in Figure 1.

Figure 4 is a similar view but showing the form in open position to receive a necktie.

35 Like characters of reference are used throughout the following specification and the accompanying drawings to designate corresponding parts.

40 My improved form for neckties comprises
a body portion 1 of flexible material formed
at opposite ends with enlargements or wings
2, which extend upward a slight distance
above the main portion of the body 1. A col-
45 lular button hole 3 is formed in the body 1 ad-
jacent its central portion, and may be of any
desired contour. The body 1 is preferably
formed of celluloid or hard rubber, so that the
same may be readily flexed, and when re-
50 leased, spring back to its original or flat posi-
tion.

A tie bar 4 is formed with a straight central shank 5, and is curved upwardly, outwardly and rearwardly at 6 adjacent the opposite ends of the central shank 5. The end portions of the bar 4 from points 4' extend downwardly slightly toward the wings 2, and then extend upwardly and outwardly as at 6'', the latter portions 6'' extending through openings 7 in the wings 2 of the body, which serve as bearings for the said bar. The extreme ends of the bar 4 are enlarged to form heads 8 which limit the endwise movement of the bar with reference to the body portion 1. 55 60

The operation of the form will now be described in detail. When it is desired to tie a bow tie on the tie bar, the bar is swung upwardly and back to the position shown in Figure 2, which movement, due to the cam action of the end portions of the bar 4 and the heads 8, will cause the body of the form 1 to bend or curve outwardly. In this position a bow tie may be easily tied on the shank of the bar. By turning the bar forwardly and outwardly, the form will spring back to a substantially flat or normal position. When the bar is turned down as shown in Fig. 1, the shank portion 5 will lie over the front surface of the form 1 and from the points 4' lie back of the wings 2, while the friction between the outwardly extended end portions 6" and the walls of the openings 7 holds the shank 5 in close contact with the form 1.

It will be understood that either a bow tie or four-in-hand tie may be equally well used with the form. 35

Many minor changes in detail of construction may be resorted to without departing from the spirit of the invention.

Having thus described my invention, what I claim as new and desire to secure by Letters Patent of the United States is:

A necktie holder comprising a body portion of resilient material having wings at opposite ends which extend above the top edge of the central part of the body portion, said wings having openings, a bar formed with a central shank which normally lies on the front surface of the body portion and provided with end portions extended upwardly and rearwardly to be over the body portion 95 100

and in rear of the wings, said end portions of the bar being further extended outwardly and upwardly to engage through the openings in the wings, and heads formed at the extreme outer ends of the bar to hold the bar and body together.

In testimony whereof I affix my signature.

THEODOR KERKHOFF.
